KILN

John T. Underwood, Alma, Ark.

Application August 27, 1931. Serial No. 559,752

11 Claims. (Cl. 25—145)

This invention relates to kilns of the round type, and has for one of its objects to improve kilns of this character to the end that the cost of building them may be materially reduced, to the end that they may contain without any increase in size more ware at each burning, and to the end that a substantial saving of fuel may be effected.

To attain the foregoing and other objects, the nature of which will appear as the description proceeds, the invention comprehends the provision of a kiln embodying a heating system which, unlike the wall furnaces and bag walls of the kilns now in use, will permit substantially all of the floor of the kiln to be utilized for ware.

The invention further comprehends the provision of a kiln of the character stated wherein the heating system shall embody a combustion chamber located below the center of the floor of the kiln, a flue located centrally within the kiln and adapted to convey the products of combustion from said chamber to a point near the top of the kiln, and an annular draft tunnel located below the floor of the kiln and communicating with the interior of the kiln near the wall of the latter, and stacks located outside the kiln and communicating with the draft tunnel.

The invention further comprehends the provision of a kiln of the character stated wherein the heating system shall embody either a gas-burner located in the combustion chamber or a fire box of semi-gas producer type located outside the kiln, and a tunnel located below the floor of the kiln for conveying the gases from the fire box to the combustion chamber.

The invention further comprehends the provision of a kiln of the character stated wherein the gas tunnel shall be of annular formation in plan and arranged in surrounding relation to the combustion chamber and in close relation to the floor of the kiln, the close arrangement of the gas tunnel to the floor of the kiln permitting the heating of the floor by the hot gases generated in the fire box.

The invention further comprehends the provision of a kiln of the character stated wherein the heating system shall embody means for delivering the air under pressure to the fire box and to the combustion chamber so as to provide an effective draft through the kiln and fire box and so as to effect the burning of all combustible gases delivered to the combustion chamber.

The invention is hereinafter fully described and claimed, and illustrated in the accompanying drawings, wherein:

Figure 1 is a sectional view taken on a plane extending vertically and centrally through the kiln constructed in accordance with my invention.

Figure 2 is a sectional view taken on the horizontal planes indicated by the line 2—2 of Figure 1.

Figure 3 is a sectional view taken on the horizontal plane indicated by the line 3—3 of Figure 1.

Figure 4 is a sectional view taken on the vertical plane indicated by the line 4—4 of Figure 2.

Figure 5 is a sectional view taken on the vertical plane indicated by the line 5—5 of Figure 2, and

Figure 6 is a sectional view illustrating the combustion chamber equipped with a gas-burner.

Referring in detail to the drawings, 1 designates the wall, 2 the floor and 3 the top of the kiln which is of the round type and which is provided below the center of its floor with a combustion chamber 4. A flue 5 extends upwardly from the combustion chamber 4 to a point near the top 3. An annular draft tunnel 6 located below the floor 2, is concentrically related to the combustion chamber 4, and is located close to the wall 1. That portion of the floor 2 located directly above the draft tunnel 6 is provided with openings 7 which establish communication between the ware firing chamber 8 of the kiln and the draft tunnel. Stacks 9 located outwardly of the firing chamber 8 communicate at their lower ends by way of passages 10 with the draft tunnel 6. The stacks 9 are equally spaced about the firing chamber 8, and the draft tunnel 6 is separated by partitions 11 into sections which communicate respectively with the respective stacks 9. The wall 1 is provided with doors 12 which permit of access to the firing chamber 8, and manholes 13 permit of access to the draft tunnel 6.

An annular gas tunnel 14 is located below the floor 2 between the combustion chamber 4 and the draft tunnel 6, and has its upper wall located close to the upper or ware supporting surface of the floor. The gas tunnel 14 communicates with the combustion chamber 4 by way of a passage 15. A deflector 16 of angular formation in horizontal section is formed on the outer side wall of the gas tunnel 14 directly opposite the passage 15, and functions to direct the gases from the tunnel into the passage. A fire box or gas generator 17 of the semi-gas producer type, is located outside of the firing chamber 8, and communicates with the gas tun-

nel 14 by way of a passage 18, this passage communicating with the gas tunnel at a point diametrically opposite the point of communication between the gas tunnel and the combustion chamber 4. The gas tunnel 14 intersects the gas tunnel 14 at 19. The gases flow from the gas tunnel 14 into the combustion chamber 4 where they are burned. The resulting products of combustion flow into the firing chamber 8 by way of the flue 5. The products of combustion flow downwardly through the firing chamber 8 into the draft tunnel 6, and flow from the draft tunnel to the stacks 9. The fire box 17 is supplied with air by a fan 20, the air being conveyed by a pipe 21 from the fan to nozzles 22 located within the fire box. A pipe 23 extends from the fan 20 to a nozzle 24 located within the combustion chamber 4 and directs sufficient air from the fan into the combustion chamber to insure the burning of all combustible gases delivered to the combustion chamber.

If desired, the fire box 17 may be omitted and natural or producer gas may be delivered by a pipe 25 to a nozzle 26 located within the combustion chamber 4. The nozzle 26 is located centrally within an air nozzle 27 to which air is delivered from a fan, not shown, by a pipe 28. With this arrangement of the gas nozzle 26 and the air nozzle 27 the gas is delivered to the combustion chamber 4 within an ascending column of air whereby the substantial complete combustion thereof is assured.

As the gas is burned in the center of the kiln comparatively little heat is lost by radiation, with the result that a substantial saving in fuel is effected. The burning of the gas in the center of the kiln obviates the necessity of the use of wall furnaces and bag walls, with the result that substantially the entire floor of the kiln may be used for supporting ware. In view thereof, the ware receiving capacity of the kiln is greater than a kiln of similar size having wall furnaces and bag walls. When the fire box 17 is employed the hot gases passing therefrom to the gas tunnel 14 will, due to the close relation of the tunnel to the floor of the kiln, heat the floor before entering the combustion chamber 4. In view thereof and as the products of combustion are delivered from the combustion chamber 4 to the firing chamber 8, a large amount of ware may be fired with a comparatively small amount of fuel. One of the advantages of my invention resides in the fact that the kiln is so constructed that ware in the central portion of the kiln will not overburn while ware around the outside of the kiln will not underburn. With my kiln, the draft flue goes around the outside circumference of the kiln or beneath the outer margin of the ware firing floor. Thus the greater part of the heat is conducted to the outside edge of kiln before it can possibly enter the stacks. The heat is not conducted directly to the stacks but is conducted around this outside margin of the kiln so that a proper amount of heat is given to this portion of the kiln and thus underburning of the ware at this point is eliminated. In my kiln no ware can be set over a furnace or heater because the main combustion chamber is disposed at the center of the kiln with the flue 5 immediately above it. Gases from the fuel being burned in the fire box 17 are conducted beneath the floor of the kiln but these are at a relatively speaking low heat as complete combustion takes place in the central chamber. When burning gas alone in my kiln, complete combustion takes place in this central chamber but if

coal be burned in the fire box partial combustion takes place in the furnace and is finished in the center chamber by the introduction of secondary air. This is possible because I have provided a mechanical control of the air supply and thus I can produce either a reducing fire by shutting off the air or a perfect oxydizing fire by supplying the proper amount of air. This is very necessary as the market requires ware of various colors and without the control of the air supply it is impossible to produce the desired colors which are brought about by a greater or less reducing condition in the kiln. With my kiln, I have absolute control of the air flow which controls the condition of the fire.

By having the draft tunnel 6 around the outside circumference of the kiln, I conduct a greater part of the heat to this outside edge. It is my opinion that no center fire kiln can be successful except by using a draft flue which goes around the kiln next to the outside walls, which outside walls are cold. My circumferentially extending draft flue compels the draft to come to the outside walls of the kiln and strike against it before it can enter the stacks.

While I have described the principle of the invention, together with the structure which I now consider the preferred embodiment thereof, it is to be understood that the structure shown is merely illustrative and that such changes may be made, when desired, as fall within the scope of the invention as claimed.

What is claimed is:—

1. A kiln comprising a ware firing chamber, a combustion chamber located at the center of and below the floor of the firing chamber, means for delivering gaseous fuel to the combustion chamber, a flue extending upwardly from the combustion chamber into the firing chamber, stacks located outside the firing chamber, and a circumferentially extending draft tunnel disposed within the outer wall and below the floor of the ware firing chamber adjacent the outer margin thereof.

2. A kiln comprising a firing chamber, a combustion chamber located below the center of the firing chamber, means for delivering gaseous fuel and air to the combustion chamber, a single flue extending upwardly from the combustion chamber into the firing chamber, stacks located outside the firing chamber, and an annular draft tunnel located below the outer margin of the ware firing chamber and communicating with the stacks and with the bottom of the firing chamber outwardly beyond the flue.

3. A kiln comprising a firing chamber, a combustion chamber located below the center of the firing chamber, means for delivering gaseous fuel and air to the combustion chamber, a flue extending upwardly from the combustion chamber into the firing chamber, stacks located outside the firing chamber, an annular draft tunnel located below the ware firing chamber and communicating with the stacks and with the bottom of the firing chamber adjacent the outer margin thereof, and partitions separating the draft tunnel into sections which communicate respectively with the respective stacks.

4. A kiln comprising a firing chamber, a combustion chamber located below the center of the firing chamber, a flue extending upwardly from the combustion chamber into the firing chamber, an annular gas tunnel located below the firing chamber and communicating with the combustion chamber, stacks communicating with

the bottom of the firing chamber, and means for delivering gas to the tunnel.

5. A kiln comprising a firing chamber, a combustion chamber located below the center of the firing chamber, a flue extending upwardly from the combustion chamber into the firing chamber, an annular gas tunnel located below the firing chamber and communicating with the combustion chamber, stacks communicating with the bottom of the firing chamber, means for delivering gas to the tunnel, and means for delivering air to the combustion chamber.

10 6. A kiln comprising a firing chamber, a combustion chamber located below the center of the firing chamber, a flue extending upwardly from the combustion chamber into the firing chamber, an annular gas tunnel located below the firing chamber and communicating with the combustion chamber, stacks communicating with the bottom of the firing chamber, a fire box located outside the firing chamber and communicating with the wall, and means for delivering air to the fire box and combustion chamber.

15 7. A kiln comprising a firing chamber, a combustion chamber located below the center of the firing chamber, a flue extending upwardly from the combustion chamber into the firing chamber, stacks communicating with the bottom of the firing chamber, an annular gas tunnel located below the firing chamber in surrounding relation to the combustion chamber, a passage extending from the tunnel to the combustion chamber, a deflector in the tunnel directly opposite said passage, and a fire box located outside the firing chamber and communicating with the wall at a point diametrically opposite the point of communication between the tunnel and passage, the tunnel being provided directly opposite its point of communication with the fire box with an inwardly offset chamber.

20 8. A kiln comprising a firing chamber, a combustion chamber located below the center of the firing chamber, a flue extending upwardly from the combustion chamber into the firing chamber, a stack communicating with the bottom of the firing chamber, an annular gas tunnel located below and close to the floor of the firing chamber and surrounding and communicating with the combustion chamber, and means for delivering

25 50 hot gases to the tunnel.

9. A kiln comprising a ware firing chamber, a combustion chamber located below the center of the firing chamber, a flue extending upwardly from the combustion chamber into the firing chamber, a stack located outwardly of the combustion chamber, a draft tunnel located below the outer margin of the combustion chamber and extending around the kiln and communicating with the interior of the kiln through the bottom thereof and with the stacks, a fire box located exteriorly of the kiln, a gas tunnel communicating with the fire box extending entirely around the central flue in spaced relation thereto and discharging into the combustion chamber, and means for regulatably discharging air into the combustion chamber.

30 10. A kiln comprising a ware firing chamber, a combustion chamber located below the center of the firing chamber, a flue extending upwardly from the combustion chamber into the firing chamber, a stack located outwardly of the combustion chamber, a draft tunnel located below the outer margin of the combustion chamber and extending around the kiln and communicating with the interior of the kiln through the bottom thereof and with the stacks, a fire box located exteriorly of the kiln, a gas tunnel communicating with the fire box extending entirely around the central flue in spaced relation thereto and discharging into the combustion chamber, and means for regulatably discharging air into the fire box and the combustion chamber.

35 11. A kiln comprising a firing chamber, a combustion chamber located below the center of the firing chamber, a flue extending upwardly from the combustion chamber into the interior of the firing chamber, an annular draft tunnel disposed beneath the floor of the firing chamber and at the outer margin thereof, the draft tunnel communicating with the interior of the firing chamber at the outer margin thereof, and at a plurality of points, draft means for carrying off the products of combustion from the draft tunnel, and auxiliary means for discharging partially burned hot gases into the combustion chamber and including a circuitous gas tunnel disposed beneath the floor of the ware firing chamber.
